Primary Examiner — T Chase Nelson*Assistant Examiner* — Dana K Weiland(74) Attorney, Agent, or Firm — Banner & Witcoff, Ltd.(57) CLAIM

The ornamental design for a display screen with icon, as shown and described.

DESCRIPTION

FIG. 1 is a front view of a first embodiment of a display screen with icon showing our new design; and, FIG. 2 is a front view of a second embodiment of a display screen with icon showing our new design. The broken lines shown in the drawings illustrate portions of the display screen with icon that form no part of the claimed design.

1 Claim, 2 Drawing Sheets(56)
